FIG.1

FIG.2

FIG.3

FIG. 4

FIG.5

FIG.6

FIG.7

FIG. 1 is a front elevation of a toy spinner with openable petals in the position which the toy assumes when in a rest position. The design on the petals resembles a pumpkin;

FIG. 2 is a rear elevation of the design;

FIG. 3 is a right end view of the design;

FIG. 4 is a top view of the design;

FIG. 5 is a bottom view of the design;

FIG. 6 is a left end elevation of the design; and

FIG. 7 shows the petals of the toy in an open position, which occurs while the spinner is in operation, exposing the head of a Halloween witch, the head being depicted

on a flat surface having substantially the same appearance from both sides.

I claim:

The ornamental design for a toy spinner with openable petals, as shown.
